UNITED STATES PATENT OFFICE

FRANK KEIDEL, OF ELMHURST, NEW YORK, ASSIGNOR TO THE INTERNATIONAL SEAL AND KNOT PROTECTOR CO., OF NEW YORK, N. Y., A CORPORATION OF NEW YORK

SEAL

Application filed May 16, 1931. Serial No. 537,763.

This invention pertains to that type of snap or automatic seal in which a flexible strap or shackle is employed carrying at one end thereof a seal body adapted to receive the other end of said strap and retain it in locked position.

One object of the present invention is to produce an efficient strap seal of the class described, which is of simple and inexpensive construction.

Other objects are to produce an automatic seal of this character which is preferably made from a single sheet of metal, and in which the members are formed by cutting and folding the metal in a simple and inexpensive manner without metal drawing operations; which does not require the use of any tools for the application and locking thereof; and which cannot be opened without tearing and mutilating the same.

In the following drawing, there is shown for the purpose of illustration, one form of device embodying the present invention.

In the drawing

Fig. 1 is a plan view of the blank from which the seal is formed.

Fig. 2 is a perspective view showing the complete seal ready to be snapped into locked position, and

Fig. 3 is a transverse section of the complete seal in locked position.

The seal is preferably formed from a single blank strip of sheet metal, stamped and bent to form a strap or shackle portion 10 and a seal locking body at one end thereof, the other end of said strap being so formed that it may be locked and retained in said seal body. In the form illustrated, this seal body 11 is constructed in accordance with the invention disclosed and broadly claimed in my prior Patent 1,783,938, issued December 2, 1930. It comprises a housing section 12, a closure section 13 having one end connected to one end of said housing section, and the other end connected to the strap 10, and an inner interlocking section 14 having one end connected to the other end of said housing section. All of said sections are formed from a single sheet of metal, and each is bent into channel shape, the sections being arranged

in series lengthwise of the blank. The section 13 is wider than the section 14, but narrower than the section 12, so that the section 14 may be locked inside of the section 12, and the locking means may be protected by the 55 positioning of both sections 13 and 14 inside of the section 12.

The section of the blank for forming the housing section 12 has side extensions which may be bent along dotted lines 15 to form 60 side walls 16. Each extension at one end is separated from the body portion by a slit 17, whereby there are formed small flap sections 18 bendable upon the dotted lines 19 to provide the inner ply of an end wall for the 65 housing section 12.

The inner interlocking section 14 which is adapted to be bent into position within the housing 12 has a body portion 26 connected to the latter by an intermediate section which 70 has a width substantially coextensive with the width of the flap sections 18, and is bent along the lines 24, so as to form the outer ply 20 of the end wall of the housing 12.

The inner section 14 preferably has extensions 21 which are bent upon dotted lines 22 to form side walls for this section, and is bent upon the dotted lines 25 to a position within the housing 12 with the top wall or body portion 26 of said section substantially in the 80 plane of the outer edges of the side walls 16 as shown in Fig. 2.

The body of the strap 10 has a section 13 which is bent in respect to the housing on a line 31. This section 13 is adapted to form a closure for the housing 12, and has side extensions 27 which are bent on the lines 28 to form side walls 29. Each of these side walls 29 is provided with an edge portion 30 bent to form inturned flanges upon the inclined edges of these side walls.

The side walls 29 and 16 are each shorter than the body portions to which they are connected, so that they are separated by two plane 95 sections 32 and 33 preferably of equal length, and extending from the fold line 31. When the seal parts are interengaged, these wall sections are spaced a slight distance to form an open ended transverse passage between 100

the fold line 31 and the ends of the side walls 16 and 29.

The end of the strap 10 opposite to the housing is provided with a transversely extending T shaped head portion including opposite extensions 34. The head is of a width and length approximately equal to the transverse passage in the housing 12, and the portion of the strap adjacent to the head is of a width not greater than the space between the flanges 30. Thus when the housing is open, the head may be placed in the transverse passage after the strap has been extended through the article to be sealed, as shown in Fig. 2. For locking this flat head end 34 of the strap 10 in the seal body, after said strap is placed in the position shown in Fig. 2, the housing 12 and its infolded section 14 are further bent along the line 31 until the inturned flanges 30 engage the upper edges of the side walls 21 as shown in Fig. 3. In this position, the side walls 29 will be disposed between the side walls of the housing 12 and the side walls 21 of the infolded section 14, and the inturned flanges 30 will engage the edges of the side walls 21 of said section 14.

It will be noted that the closure section 13 embraces the infolded section 14 to protect the locking engagement of the inturned flanges with the edges of the infolded section 14, and prevents the release of this locking engagement without the mutilation of the parts to such an extent as would render them unfit for further use. The head end of the strap 10 will be clamped between the sections 32 and 33, and will be held against longitudinal movement by the abutment of the transverse edges of the head 34 with the inner ends of the side walls 29 and 16, and the fold line 31. If desired, this strap 10 may be provided with one or more holes 35 intermediate of the ends thereof, so as to weaken said strap, and facilitate the bending thereof along opposite sides of said holes into the position shown in Fig. 2.

It will be noted that the entire device is formed of a single piece of metal, that the forming is done entirely by cutting and bending without drawing operations, that the seal may be applied and locked by a bending operation easily effected by the fingers without the use of tools, that after the seal is locked, it cannot be opened without breaking or telltale mutilation, and that the entire device is easy and cheap to manufacture, and very efficient in operation.

In the specific construction illustrated in the drawing, the housing at one end of the strap has certain features similar to those shown and broadly claimed in my prior Patent 1,783,938, issued December 2, 1930. The housing of my present seal may be triangular in longitudinal section with the parts proportioned as in Figs. 1-5 inclusive,

of said patent, or may be rectangular in longitudinal section with the parts proportioned as shown in Figs. 6, 7 and 8 of said patent. Various other forms of sealing means may be employed within the scope of my present invention.

Having thus described my invention, what I claim as new and desire to secure by Letters Patent is:—

1. A seal including a strap having at one end thereof a transversely extending head, and at the other end thereof a seal body including two interconnected sections bendable along a transverse line therebetween, said sections having means integral therewith along the side edges thereof and spaced from said transverse line for automatically locking them together when said two sections are brought together by bending along said bendable line, said head being adapted to be placed between said transverse line and said locking means, and held therein against movement endwise of said strap, whereby said head may be automatically locked between said sections, and between said bendable line and said locking means when the two sections are snapped together by bending along said line.

2. A seal including a strap having a head at one end, a seal body connected to the other end of said strap, and adapted to lock said head therein, said seal body including two interconnected sections bendable along a transverse line therebetween, and having interlocking side walls the ends of which are spaced from said line, the other end of said strap being narrow enough to permit its reception between said side walls, with said head between said bendable line and said side walls, said head being wide enough to abut the end edges of said side walls when in locked position, so that said head will be held between said walls and the portion of the seal adjoining the transverse line, against movement endwise of said strap.

3. A seal including a strap, and having one end provided with a head extending transversely therefrom, and presenting a transverse shoulder spaced from the end, a seal body connected to the other end of said strap, and including two sections connected end to end adapted to fold into superposed relationship with said head therebetween, each of said sections having a pair of side walls spaced endwise from the fold line between said sections to a distance greater than the distance between said shoulders and the end of the head to receive said head between said sections with said shoulder engaging the end edges of the side walls of one of said sections, and means for locking said side walls of one section to the side walls of the other section, with said head between said sections.

4. A seal including a strap having a pair

of flanges on the opposite sides adjacent to but spaced from one end, and extending in parallel planes at right angles to the plane of the body of said strap, the opposite end of the strap being adapted to be disposed between said flanges and provided with a **T** head of a width greater than the distance between said flanges, the terminal portion of said first mentioned end being adapted to be folded over onto said head to confine the head between the fold line and the end edges of said flanges, and having means integral therewith for automatically interlocking with said flanges to prevent lifting of said terminal portion, and thereby retain said head in position.

Signed at New York, in the county of New York and State of New York this 13th day of May A. D. 1931.
